JUICE EXTRACTOR

Carl H. Steinbiss, Milwaukee, Wis., assignor to
Max Hauser, Milwaukee, Wis.

Application May 7, 1934, Serial No. 724,417

5 Claims. (Cl. 100—48)

This invention relates to improvements in juice extractors.

The objects of the invention relate rather specifically to the improvement of the mechanical construction of juice extractors employing a screw for advancing the pulp, means for affording variable resistance to the escape of the pulp, and means for collecting and discharging the juice.

10 By means of the present invention it is sought to improve the form of the casting which comprises the compression chamber and provides the discharge spouts leading therefrom; to provide for an assembly of parts which facilitates 15 the cleaning of the extraction chamber, and the associated parts of the device; to facilitate the application and removal of the screw; to provide an improved type of strainer; and to minimize the possibility of the escape of juice along 20 the bearings of the screw.

In the drawing:

Figure 1 shows the device partially in side elevation and partially in vertical section axially of the screw.

25 Figure 2 is a view taken in a section in a plane indicated at 2—2 in Figure 1.

Figure 3 is a view in horizontal axial section through the juice extraction chamber.

Figure 4 is a detail view on a large scale showing 30 the rear end of the exterior chamber in elevation.

Like parts are designated by the same reference characters throughout the several views.

The body of the device comprises a casting 5 which includes integrally a hopper 6, a juice extraction chamber 7, a juice collecting chamber 8, a support 9, and a C clamp bracket 10. The movable portion of the clamp comprises the conventional screw 11 and hand wheel 12.

40 The screw 15 comprises a helical thread 16 wound upon a shaft 17, which increases in cross section from the rear end of the device toward the forward end thereof, whereby gradually to reduce the capacity of the compression chamber

45 7. The shaft is provided integrally with collars 18 at its rear end and 19 at its forward end, which are fitted closely into complementary bearings 20 and 21, respectively, which are formed in the casting 5.

50 The collars are peripherally grooved at 22 and the bearing surface 21 has a complementary undercut groove at 24, the grooves being adapted to collect any juice tending to flow past the bearings, and thereby to escape from the juice extraction chamber. The grooves are drained by pas-

sages 25 and 26, respectively, through the juice collecting chamber 8.

Beyond the integral collar 20, the shaft 17 carries unitarily a key 30, which has radially projecting lugs at 31 releasably engageable behind the flanges 32, which are formed integrally with casting 5, as best shown in Figures 3 and 4. The key includes a hand lever 34 which facilitates its oscillation about shaft 17, whereby the lugs 31 may either be registered with the spaced flanges 32, as shown in Figure 4, for the removal of the shaft and screw, or may be locked behind such flanges to provide a thrust bearing to receive the axial thrust of the screw.

The key 30 is unitarily held in assembled relation to the shaft by means of the handle 35 used for the rotation of the shaft, the hub portion of the handle being permanently secured to the shaft by a cross pin 36 as shown in Figure 1. When the key 30 is moved to the unlocked position shown in Figure 4, the handle 35 and the shaft 15 may be withdrawn axially from the casting 5 toward the rear.

At the side of the forward end portion of the casting is a port 38 through which the pulp escapes under the regulation of a screw 39 which is threaded into a boss 40 comprising an integral part of casting 5. As is clearly indicated in Figure 2, the raising of screw 39 will increase the effective capacity of the port 38. While in the 30 position illustrated in Figure 2, the screw substantially crosses port 38. Below screw 39, the casting 5 is integrally provided with a discharge spout 41, beneath which a dish may be placed to collect the pulp.

The juice extracted from the pulp by the operation of the screw 15 thereon is separated from the pulp by means of the strainer 42 which comprises the partition between the extraction chamber 7 and the juice collecting chamber 8. Since 40 it is necessary that this strainer would stand a considerable degree of pressure, means is provided to reinforce it. The strainer comprises a foraminous plate bent to an arcuate form in cross section, as best appears in Figure 2, to conform 45 to the path of travel of the peripheral portion of thread 16. The marginal portions of the screen rest in shallow recesses formed at 43 in the interior wall of the chamber 7.

In order to maintain the screen properly centered in its recesses, while at the same time reinforcing the central portions of the screen, a rib is made by folding the intermediate portion of the screen at 45. This rib is received into the notches 46 and 47 formed between the endmost 55

lugs 48 and 49 of a series of lugs 50 disposed at intervals along the sides of casting 5 to provide additional support for the screen.

The bottom of the juice collecting chamber 8 5 below the screen is closed, except at the forward end of such chamber, where it drains into a spout 52, which is opposite a pulp discharge spout 41.

To prevent the pulp from rotating with the screw in chamber 7, the said chamber is preferably longitudinally grooved at 53, as best shown in Figure 2.

The device is usable to extract the juice from practically any fruit or vegetable fed to it in pieces of such size as will be receivable into the hopper 6. The resistance offered to the escape of the pulp by means of the adjustable screw 39 will determine the extent to which the juice will be extracted therefrom.

The fact that the key 30 is unitarily assembled 20 with the handle 35 and screw 15 is a factor contributing to the facility with which the device may be cleaned. It will be noted that the key constitutes an instantly detachable means for positively anchoring the screw, and when this key 25 is turned to its figure 4 position, there are very few parts of the apparatus requiring separate handling in the removal of the screw for the cleansing of the screw and the rest of the apparatus.

30 I claim:

1. In a juice extractor, the combination with a casing providing a cylindrical extraction chamber, a juice collecting chamber therebeneath and an opening affording communication between said chambers, said casing providing ports at one end of the casing opening in opposite directions laterally from the extraction chamber and the juice collecting chamber respectively, a screen comprising a partition across said opening between said chambers, a screw in the extraction chamber, and means integral with said casing providing delivery spouts for pulp and juice, said means comprising a wall connected with said casing and inclined downwardly and outwardly from one of said ports, and a second wall connected with said first wall intermediate its upper and lower ends and extending laterally beneath the other of said ports.

2. In a juice extractor, the combination with a feed screw; of a chamber casting providing bearings for said screw, a hopper inlet, an extraction chamber in which said screw is disposed, said chamber being of a form generally circular in cross section and provided with a discharge slot in its bottom, a juice collecting chamber therebeneath, and a pulp discharge port in its side adjacent the end remote from the hopper; a removable strainer provided with means for its support to span the slot between the extraction chamber and the juice collecting chamber of said casting; a control screw threaded to said casting and adjustable substantially tangentially of said feed screw across the pulp discharge port; and an extension wall on said casting providing a laterally opening spout communicating with said juice collecting chamber and to which said juice collecting chamber drains, the head of said wall also comprising a second spout leading laterally

from said pulp discharge port to receive material issuing therefrom under the control of said control screw.

3. In a juice extractor, the combination with a casing having a cylindrically walled portion comprising an extraction chamber, and a juice collecting chamber, said juice collecting chamber positioned beneath said extraction chamber and having an opening affording communication between said chambers, a series of lugs projecting centrally of said casing from the side walls thereof adjacent said opening, a screen supported on said lugs and extending across said opening, said screen being of arcuate form generally conforming to the shape of the extraction chamber, 15 a reinforcing rib extending longitudinally of said screen on the under surface thereof between the said lugs, and supporting means integral with said casing for the ends of said screen, said supporting means being notched to receive said rib. 20

4. In a juice extractor, the combination with a rotatable screw, of a chamber having inlet and outlet ends, the inlet end being provided with a feed hopper, and provided adjacent said ends with bearings for said screw, said chamber having 25 a restricted discharge opening comprising a substantially vertical slot in its side wall adjacent the bearing of the discharge end thereof and also having a foraminous bottom wall extending beneath said screw past said slot substantially to 30 said last mentioned bearing, a juice collector beneath said foraminous wall, and a control screw adjustable lengthwise of said slot and substantially tangential with respect to said screw to regulate the resistance to discharge of solids through said 35 slot, said slot being elevated above said foraminous wall to facilitate the expression of all juices through said wall to said collector.

5. In a juice extractor, the combination of a chamber having inlet and discharge ends and 40 provided with bearings at said ends and with a hopper adjacent the inlet end, and a substantially upright slot adjacent the bearing at the discharge end, means integral with said chamber 45 providing a juice collecting receptacle therebeneath and communicating with said chamber substantially throughout the length thereof, discharge spouts leading from the juice collector and from such slot in opposite lateral directions, a foraminous wall comprising a partition between 50 said expression chamber and said juice collector, said wall being arcuate and substantially concentric with the axis of said bearings, an expression screw operable in said bearings, and a second screw comprising a gate threaded to a portion of 55 said chamber and extending longitudinally of said slot and substantially tangential with respect to said expression screw, whereby to control the resistance to discharge of solids through said slot, said slot being located substantially above said foraminous wall and said wall being continued past said slot substantially to the bearing at the discharge end of the chamber, whereby to facilitate the complete expression of all 60 juices from solids in said expression chamber and the delivery of such juices through said wall instead of through said slot.

CARL H. STEINBISS.
